UNITED STATES PATENT OFFICE.

THOMAS M. TORSON, OF KANSAS CITY, KANSAS.

WINDLASS.

1,142,738.

Specification of Letters Patent.

Patented June 8, 1915.

Application filed February 25, 1914. Serial No. 820,919.

To all whom it may concern:

Be it known that I, THOMAS MARTIN TORSON, a citizen of the United States, residing at Kansas City, in the county of Wyandotte 5 and State of Kansas, have invented certain new and useful Improvements in Windlasses; and I do hereby declare the following to be a full, clear, and exact description of the invention, such as will enable others 10 skilled in the art to which it appertains to make and use the same.

My invention relates to new and useful improvements in windlasses and resides in the provision of a novel form of windlass 15 which is provided with a removable winding drum that may be readily turned so that the handle connected therewith is disposed upon either side of the supporting frame for the windlass and readily positioned upon the 20 supporting frame without necessitating the employing of bolts and nuts or other means for holding the windlass in secure operative position upon the frame.

An important object of my invention is to 25 provide a windlass of the character described which is arranged to be supported by a novel form of supporting frame and consists of a winding drum having extensions thereon that are arranged to be fitted 30 within the supporting frame so as to be readily removable therefrom and that it may be turned or reversed without necessitating the turning of the device as a whole.

In excavating work, it is necessary that 35 the dirt should be taken out upon both sides of the excavation, in some instances, and in employing a windlass for this excavating work it requires four or more men as a general rule to turn the windlass around 40 so that the handle is disposed upon the opposite side: my invention therefore, aims to provide a windlass which is so arranged and constructed as to obviate the necessity of the operation before described.

45 Another important object of my invention is to provide a simple and inexpensive windlass which is reliable and efficient in operation, and capable of being cheaply manufactured.

50 The above and additional objects are accomplished by such means as are illustrated in the accompanying drawings, described in the following specification and then more particularly pointed out in the claim which

is appended hereto and forms a part of this 55 application.

With reference to the drawings, wherein I have illustrated the preferred embodiment of my invention as it is reduced to practice, and throughout the several views of which 60 similar reference numerals designate corresponding parts: Figure 1 is a detail side elevation of my improved windlass showing it removed from the supporting frame. Fig. 2 is a front elevation of my improved wind- 65 lass showing it in assembled position. Fig. 3 is a side elevation thereof.

Referring to the drawings the numeral 1 designates as an entirety a supporting frame. This supporting frame 1 comprises a rectangular frame comprising four bars 2 that are preferably screw threaded at their terminals and connected with each other by suitable couplings 3. Certain opposed bars 2 are connected centrally of their ends by 70 means of suitable couplings or connecting 75 mediums 4 to vertical tubular rods 5 and 6 that are opposite one another.

The upper ends of the rods 5 and 6 are arranged to receive the winding drum after 80 a manner which will be later more fully described.

Removably mounted upon the rods 5 and 6 is a winding drum designated 7 as an entirety. The shaft 8 of this drum 7 is journaled at its ends in cylindrical bearings 9. A tubular right angular extension 10 is carried by each bearing 9 and in turn carries an extension rod 11. The rods 11 are of slightly less diameter than the internal 85 diameter of the rods 5 and 6 and are arranged to fit within the upper end of the rods 5 and 6 so as to hold the drum firmly in 90 position upon the frame 1. The extensions 10 form a shoulder for the rods 11 and engage the upper ends of the rods 5 and 6. 95

The rods 11 form handholds when the drum is removed from the uprights 5 and 6 so that the drum can be conveniently held in suspended position and turned and read- 100 ily positioned again on the upright.

A crank handle 12 is carried upon one side of the drum shaft 8 and provides for the rotation of the drum 7. A rope or cable 13 is secured at one end upon the drum and 105 arranged to be wound thereon and at its other end carries a bucket supporting member 14 which consists of a ring like body

portion 15 provided with an arcuate connecting bar 16 which is secured intermediate and approximately centrally of its ends to a hook 17 that is carried upon the free end 5 of the rope or cable 13.

It will be readily seen that when it is desired to move the handle 12 from one side to the other of the frame, the operator simply lifts the drum 7 sufficiently to move the 10 rods 11 out of the tubular rods 5 and 6. The drum 7 is free to be turned around and the rods 11 are then fitted within the rods 5 and 6.

With reference to the foregoing description and accompanying drawings it will be 15 readily seen that I have provided a novel form of windlass which is so constructed as to eliminate the necessity of turning the windlass as a whole around when it is desired to operate upon both sides of an excavation. It will also be noted that it is not necessary to employ bolts or other fastening means for the purpose of securing the winding drum upon the supporting 20 frame of my device, since the extension rods 11 in telescoping within the upper ends of the rods 5 and 6 provide a firm bearing for the drum 7.

In reduction to practice, I have found that 25 the form of my invention, illustrated in the drawings and referred to in the above de-

scription, as the preferred embodiment, is the most efficient and practical; yet realizing that the conditions concurrent with the adoption of my device will necessarily vary, 35 I desire to emphasize the fact that various minor changes in details of construction, proportion and arrangement of parts may be resorted to, when required, without sacrificing any of the advantages of my invention, 40 as defined in the appended claim.

What is claimed is:—

A windlass comprising a supporting base having a pair of spaced tubular uprights thereon, a drum carrying shaft located at 45 the upper end of the uprights, bearings for receiving the opposite ends of the shaft, rods extending from the bearings and adapted to be received by the tubular uprights and having shoulders formed thereon to engage 50 the upper ends of the uprights so as to limit the downward movement of the rods within the uprights, said rods being adapted to provide handholds for the drum carrying shaft when the latter is removed from the 55 uprights.

In testimony whereof I affix my signature in presence of two witnesses.

THOMAS M. TORSON.
